HERBERT C. COLBURN, OF COLORADO SPRINGS, AND ERNEST A. COLBURN, OF DENVER, COLORADO.

ORE-FLOTATION APPARATUS.

1,226,063.

Specification of Letters Patent.

Patented May 15, 1917.

Original application filed May 31, 1916, Serial No. 100,947. Divided and this application filed October 31, 1916. Serial No. 128,721.

To all whom it may concern:

Be it known that we, HERBERT C. COLBURN, residing at Colorado Springs, in the county of El Paso and State of Colorado, and ERNEST A. COLBURN, residing at Denver, in the county of Denver and State of Colorado, citizens of the United States, have invented new and useful Improvements in Ore-Flotation Apparatus, of which the following is a specification.

This invention relates to apparatus for separating valuable particles in finely divided ore, by what is commonly known as the flotation process.

15 This application is divisional of our application Serial Number 100,947, on ore flotation process, filed May 31, 1916, and allowed October 17, 1916, it being the object of the present invention to provide an association 20 of simple mechanical devices by which our separation process may be effectually carried out.

The process above referred to consists in mixing ore pulp with an oil or other substance 25 having a selective affinity for the desired valuable particles, agitating and emulsifying this mixture with the addition of a limited quantity of air or other gas, under a pressure less than atmospheric, and then conducting the emulsified mixture to a separate receptacle in which the froth can rise under atmospheric pressure.

In order to carry out this process we have 35 designed an apparatus the principal elements of which are a settling tank the contents of which are under atmospheric pressure and a mixing chamber provided with an outlet which connects with a settling tank and with an inlet for ore-pulp which connects with a conveniently disposed supply of 40 ore and water.

The mixing chamber contains a movable element adapted to thoroughly agitate and emulsify its contents, and suitable means are 45 provided to maintain during the agitative action, a partial vacuum in the chamber which greatly expedites and promotes the process of separation.

By subjecting the finely divided ore during 50 the emulsification step of the process, to a partial vacuum, the envelopes of gas and colloidal matter which surround the sulfid

particles contained in the ore are expanded and disrupted and the oil having a natural affinity for the sulfids, immediately attaches 55 itself thereto after the particles have been bared.

The partial vacuum constantly maintained in the mixing chamber, furthermore atomizes the air through the pulp and produces 60 other results of minor advantage, all of which coöperate in obtaining a product which upon entering the settling chamber will by natural flotation be cleanly divided, it being understood that the oil-coated sulfid 65 particles, as a direct result of the mixing action under less than atmospheric pressure, will rise naturally and easily to the surface while the gangue settles to the bottom of the tank. The air atomized through the pulp 70 also rises to the surface of the material in the settling chamber and a froth is formed in which the values are entrapped and which may be removed from the tank either by natural overflow or by the use of a suitable 75 skimming device.

The partial vacuum required in the mixing chamber during the emulsification process is preferably obtained by providing the chamber with an outlet-opening which exceeds the feed opening in area, a proportion of four to one having been found to produce satisfactory results.

The partial vacuum may also be obtained by connecting the mixing chamber with a 85 suction pump through the intermediary of a vacuum chamber, or by any other expedient which may be found best adapted for the purpose.

The oil and air are admitted to the material under treatment, preferably through openings in the conduit which connects with the inlet opening of the mixing chamber, the flow through said openings being controlled by valves which are connected 95 for synchronous movement to automatically proportionate the quantities of oil and air admitted during a given period in the operation of the apparatus.

Having thus briefly described the purposes, operation and results of our improved apparatus, we will now proceed to explain the construction of the same in detail with reference to the accompanying

drawings in the various views of which like parts are similarly designated, and in which

5 Figure 1 represents a sectional elevation of the elements comprised in the apparatus, in their coöperative relation,

Fig. 2, a vertical section through the mixing chamber of the apparatus taken along the line 2—2, Fig. 1, drawn to an enlarged scale,

10 Fig. 3, a section along the line 3—3, Fig. 2, and

15 Fig. 4, a sectional elevation showing a means for maintaining a partial vacuum in the mixing chamber by means of a suction pump and a vacuum tank interposed between the pump and the mixing chamber.

20 Referring to the drawings by numerical reference characters, 2 designates the settling tank of the apparatus which is preferably made in the form of a spitzkasten. The tank has at its upper edge an overflow 3 for the froth produced in the flotation process, and in its bottom an outlet 4 for the settling gangue.

25 The mixing chamber 5 of the apparatus consists in its preferred form of an upright circular casing 6 in which a mixing element has a rotary movement about a horizontal axis. The casing has a feed opening 7 which by means of a conduit 8 is connected with an elevated source of ore supply 9, and an outlet 10 of comparatively large diameter, which connects with a conduit 12 extending into the settling or frothing tank 2.

30 The mixing element may be of any suitable construction, preference being given to a device of the character shown in Figs. 2 and 3 of the drawings.

35 The feed opening 7 of the mixing chamber is in this construction formed centrally in one of the sides of the casing 6, and the outlet opening 10 is disposed tangentially at the upper end of the same. The feed-opening is connected with the before mentioned conduit 8 by a nozzle 13 the cross-sectional area of which is less than one-fourth the area of the outlet 10.

40 The nozzle has an opening for the admission of air the flow through which is controlled by a valve 14 which is yieldingly held upon its seat against atmospheric pressure by a spring 15.

45 The oil used in the flotation process, enters the nozzle through an opening the admission of oil to which is controlled by a needle-valve 16 which opens and closes the outlet of a pipe 17 communicating with the source of oil supply.

50 The two valves are connected to move in unison by a lever 18, whereby the quantities of air and oil admitted at one time to the material passing through the nozzle, are automatically proportioned.

55 The spring 15 is made of sufficient strength to maintain the partial vacuum in

the mixing chamber constantly at a predetermined pressure.

60 The casing 6 has centrally disposed stuffing boxes 19 for the support of a shaft 20 which imparts a rotary movement to the mixing element within the chamber 5.

65 This element consists of a disk-shaped member 21 mounted on the shaft 20 and provided with a series of radial, outwardly projecting vanes 22 which in their outer longitudinal edges have recesses to admit correspondingly formed tongues 23 on a stationary member 24 which is fixed at the opposite side of the chamber.

70 During rotation of the shaft these tongues pass through the recesses of the rapidly rotating member 21 and thereby effect a thorough agitation and emulsification of the ore pulp, oil and air.

75 In the construction shown in Fig. 4, a mixing chamber 25 is connected by a conduit 26 with a reservoir 27 in which a vacuum of determinate pressure is maintained by a suction pump 28. The mixing element mounted within the chamber 25 consists of a series 80 of paddles which radiate from a rotary vertical shaft 29.

85 In the operation of our apparatus, the ore-pulp, oil and air are introduced into the mixing chamber in predetermined proportions as hereinbefore explained, the partial vacuum maintained in the mixing chamber bares the sulfids of the ore, which are immediately coated with oil, and the entire mass contained in the chamber is thoroughly 90 agitated and emulsified and intermixed with the air or other gas which is atomized by the vacuum.

95 The mixture is discharged from the mixing chamber into the settling tank in which it is brought to a comparative condition of rest and in which the coated sulfid particles and atomized air rise to the surface where they congregate into a froth in which the values of the ore are entrapped. The froth 100 passes across the overflow into a launder 30 and its movement may be expedited by the use of a skimmer such as that shown at 31 in Fig. 1.

105 The gangue settling to the bottom of the settling tank is discharged at intervals through the normally valve-closed outlet 4.

110 While in most cases a single treatment of the ore by our process is sufficient to extract practically all the values it contains, the 115 treatment of unusually refractory ores may be repeated by the use of a second apparatus similar to that described, the mixing chamber of which connects with the gangue outlet of the settling tank of the first apparatus. The two settling tanks may under these 120 conditions be connected by a conduit 32 for maintaining their liquid contents on an even level.

125 Having thus described our invention what 130

we claim and desire to secure by Letters-Patent is:

1. Apparatus for separating valuable particles of finely divided ores by a flotation process, comprising in combination, a mixing chamber having a feed-opening and an outlet, a mixing element operating in said mixing chamber for the agitation and emulsification of its contents, means for maintaining a partial vacuum in the mixing chamber during the operation of said element, and a settling chamber under a higher pressure, connected with said outlet.

2. Apparatus for separating valuable particles of finely divided ores by a flotation process, comprising in combination, a mixing chamber having a feed-opening, an inlet for introducing a gas into material admitted through said feed-opening, and an outlet, a mixing element operating in said mixing chamber for the agitation and emulsification of its contents, means for maintaining a partial vacuum in the mixing chamber during the operation of said element, and a settling chamber under a higher pressure, connected with said outlet.

3. Apparatus for separating valuable particles of finely divided ores by a flotation process, comprising in combination, a mixing chamber having a feed-opening, an inlet for introducing a substance having a selective affinity for the desired valuable particles, into material admitted through said feed-opening, and an outlet, a mixing element operating in said mixing chamber for the agitation and emulsification of its contents, means for maintaining a partial vacuum in the mixing chamber during the operation of said element, and a settling chamber under a higher pressure, connected with said outlet.

4. Apparatus for separating valuable particles of finely divided ores by a flotation process, comprising in combination, a mixing chamber having a feed-opening, an inlet for introducing an oil into material admitted through said feed-opening, and an outlet, a mixing element operating in said mixing chamber for the agitation and emulsification of its contents, means for maintaining a partial vacuum in the mixing chamber during the operation of said element, and a settling chamber under a higher pressure, connected with said outlet.

5. Apparatus for separating valuable particles of finely divided ores by a flotation process, comprising in combination, a mixing chamber having a feed-opening, inlets for introducing a gas and an oil into material admitted through said feed-opening, and an outlet, a mixing element operating in said mixing chamber for the agitation and emulsification of its contents, means for maintaining a partial vacuum in the mixing chamber during the operation of said element, and a settling chamber under a higher pressure, connected with said outlet.

ment, and a settling chamber under a higher pressure, connected with said outlet.

6. Apparatus for separating valuable particles of finely divided ores by a flotation process, comprising in combination, a mixing chamber having a feed-opening, an inlet for introducing a gas into material admitted through said feed-opening, and an outlet, a mixing element operating in said mixing chamber for the agitation and emulsification of its contents, means for maintaining a partial vacuum in the mixing chamber during the operation of said element, a valve automatically regulating the admission of a gas through said inlet, and a settling chamber under a higher pressure, connected with said outlet.

7. Apparatus for separating valuable particles of finely divided ores by a flotation process, comprising in combination, a mixing chamber having a feed-opening, inlets for introducing a gas and an oil into material admitted through said feed-opening, and an outlet, a mixing element operating in said mixing chamber for the agitation and emulsification of its contents, means for maintaining a partial vacuum in the mixing chamber during the operation of said element, a valve automatically regulating the introduction of a gas through the gas-inlet, a valve co-operating with the other valve to regulate the introduction of oil through the oil-inlet, and a settling chamber under a higher pressure, connected with said outlet.

8. Apparatus for separating valuable particles of finely divided ores by a flotation process, comprising in combination, a mixing chamber having a feed-opening and an outlet, a mixing-element operating in said mixing chamber for the agitation and emulsification of its contents, said feed-opening being relative to said outlet, of reduced area for maintaining a partial vacuum in the mixing chamber during the operation of said element, and a settling chamber under a higher pressure, connected with said outlet.

9. Apparatus for separating valuable particles of finely divided ores by a flotation process, comprising in combination, a mixing chamber having a feed-opening and an outlet, a mixing element operating in said mixing chamber for the agitation and emulsification of its contents, said feed-opening having an area not exceeding one-fourth the area of said outlet for maintaining a partial vacuum in the mixing chamber during the operation of said element, and a settling chamber under a higher pressure, connected with said outlet.

10. Apparatus for separating valuable particles of finely divided ores by a flotation process, comprising in combination, a mixing chamber having a feed-opening and an

- outlet, a mixing element operating in said mixing chamber and comprising a rotary member and a fixed member having intermeshing parts for the agitation and emulsification of the contents of said chamber, means for maintaining a partial vacuum in the mixing chamber during the operation of said element, and a settling chamber under a higher pressure, connected with said outlet.
11. Apparatus for separating valuable particles of finely divided ores by a flotation process, comprising in combination, a mixing chamber having a feed-opening and an outlet, a mixing element operating in said mixing chamber and comprising a rotary member and a fixed member having cooperative vanes for the agitation and emulsification of the contents of said chamber, means for maintaining a partial vacuum in the mixing chamber during the operation of said element, and a settling chamber under a higher pressure, connected with said outlet.

12. Apparatus for separating valuable particles of finely divided ores by a flotation process, comprising in combination, a mixing chamber having a feed-opening and an outlet, a mixing element operating in said mixing chamber for the agitation and emulsification of its contents, means for maintaining a partial vacuum in the mixing chamber during the operation of said element, a settling chamber under a higher pressure, connected with said outlet, and means for feeding material into the mixing chamber by gravitation and discharging the mixture produced in the latter, into the settling chamber.

In testimony whereof we have affixed our signatures in presence of two witnesses.
